COMBINED CAMERA STAND AND PHOTOFFLASH HOLDER

Cecil Frederick Adickes, Jr., Pleasant Ridge, and Donald J. Reid, Troy, Mich., assignors to Cradle Pictures, Inc., Detroit, Mich.

Filed Jan. 3, 1962, Ser. No. 68,175

Term of patent 14 years

(Cl. D61—1)

FIG. 1 is a side elevational view of a combined camera stand and photoflash holder showing our new design, the opposite side being substantially a mirror image thereof;

FIG. 2 is a front elevational view thereof;

FIG. 3 is a top plan view of the base thereof, taken on line 3—3 of FIG. 1; and

FIG. 4 is an enlarged fragmentary perspective view of the combined camera stand and photoflash holder showing the head portion thereof.

The top, bottom, and rear surfaces of the head, not shown, are substantially plain and unornamented.

We claim:

The ornamental design for a combined camera stand and photoflash holder, as shown and described.
